UNITED STATES PATENT OFFICE.

HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

MARINE TURBINE.

Application filed March 7, 1921. Serial No. 450,239.

To all whom it may concern:

Be it known that I, HENRY F. SCHMIDT, a citizen of the United States, and a resident of Swarthmore, in the county of Delaware and State of Pennsylvania, have invented a new and useful Improvement in Marine Turbines, of which the following is a specification.

My invention relates to a turbine installation, particularly of the marine type, employing a plurality of turbine units, and has for its object to provide apparatus of the character designated in which substantially equal powers are developed with good efficiency in each unit at different speeds.

The single figure of the accompanying drawing is a diagrammatic representation of a turbine installation showing my improvements applied thereto.

It is common practice to compound turbines in various ways, both for land and marine use; however, in marine practice, it is usual to provide a separate turbine for cruising speeds, and, if a plurality of propeller shafts is employed, it becomes a difficult matter to provide an installation in which equal powers and speeds are developed in each propeller shaft. Accordingly, it is the object of my invention to provide a multiple-unit turbine installation in which each unit is connected to a propeller and to so distribute the motive fluid flowing in series therethrough that equal powers and speeds are developed in each unit, thereby avoiding the necessity of operating the helm with consequent loss in efficiency, as is the usual practice, when one propeller has greater power applied thereto than to the other.

Referring now more particularly to the drawings for a detailed description of my invention, I show a high-pressure turbine unit 9 having a rotor 10 and a low-pressure turbine unit 11 having a rotor 12. The high-pressure unit comprises a partial-peripheral impulse section 13 and full peripheral admission sections 14 and 15 and the low-pressure unit includes full peripheral admission sections 16 and 17. Motive

fluid is expanded in series through the two units in a manner to be more particularly hereinafter set forth. The rotors 10 and 12 are connected to the propellers 18 and 19, respectively, by any appropriate means as, for example, reduction gearing 20 and 21.

The initial impulse section 13 of the high-pressure unit 9 receives motive fluid from one or more expanding nozzles 23, supplied by appropriate motive fluid connections 24, controlled by valves 25. After having its velocity energy fractionally abstracted by the impulse section 13, motive fluid then flows through the high-pressure and intermediate-pressure full-peripheral admission reaction sections 14 and 15 and from the latter into an exhaust casing 26.

The turbine unit 11 receives motive fluid from the exhaust casing 26 through a conduit or receiver passage 27 provided with a controlling valve 28. Beyond the valve 28 and adjacent the section 16 of the low-pressure turbine unit 11, the conduit is divided into a plurality of branches 29, 30, and 31 discharging at different points along the section 16 in order to build up different back pressures in the exhaust casing 26 as well as to include different numbers of rows of blading in series with the high-pressure turbine unit, it being apparent that, since the blading in section 16 is shorter than that of the last row of the high-pressure turbine unit, a back pressure will be built up in the exhaust casing 26. The branch 29 is connected with the high-pressure end of the section 16, the branch 30 is connected with said section at an intermediate point, and the branch 31 is connected with the section 16 at a point near the low-pressure end.

With the valve 28 open, motive fluid may be passed through one or more of the branches 29, 30, and 31, the valves 32, 33, and 34 carried by the respective branches being appropriately manipulated for that purpose. For high speed operation, the valve 34 is opened and the valves 32 and 33 are closed, the branch 31 being so located with reference to section 16 that a back pressure is built up in the casing 26 suf-

- ficient to cause an equal development of power by the turbine units. For an intermediate speed, the valve 32 is closed, the valve 33 is opened, and the valve 34 is opened to a sufficient degree to secure equal speeds of the rotors. For low speed, the valve 32 is opened and the valve 34 closed, the valve 33 being opened sufficiently to develop equal speeds of the two turbine units.
- 10 A slightly higher speed than that last referred to may be secured, with the valve 32 open and the valve 33 closed, by opening the valve 34 to a degree sufficient to develop equal powers by the two rotors.
- 15 The low-pressure unit preferably discharges into the exhaust casing 36. The rotor 10 carries a reversing impulse wheel 40 provided with peripheral buckets adapted to receive motive fluid from an expanding nozzle 41, the latter being supplied by any appropriate connection 42 having a controlling valve 43. The rotor 12, in like manner, is provided with a reversing impulse wheel 44 receiving motive fluid from an expanding nozzle 45 supplied by a conduit 46 under the control of a valve 47.
- 20 The low-pressure turbine unit 11 is also provided with an independent motive fluid inlet 50 under the control of the valve 51 so that motive fluid may be supplied thereto for maneuvering or emergency purposes.
- 25 The exhaust casing 26 is connected to the exhaust casing 36 by means of a passage or conduit 37 under the control of a valve 38, the valve being normally closed so as to compel motive fluid to pass in series through the low-pressure turbine unit 11. When running astern, the valve 38 is opened and the valve 28 is closed, motive fluid passing from the exhaust casing 26 through the passage 37 to the exhaust casing 36 and from the latter through an appropriate exhaust connection 39 to a condenser (not shown).
- 30 When maneuvering, motive fluid being supplied to both turbine units 9 and 11 from the high-pressure connections 24 and 50, the valve 28 should be closed and the valve 38 opened in order to permit the exhaust from the casing 26 to pass through the conduit 37 to the casing 36 and from the latter through the exhaust outlet 39 to the condenser (not shown).
- 35 It is desirable to have the valves 28 and 38 under the control of the valves 51, 43, and 47 so that, when any of the latter valves is opened, the valve 28 is closed and the valve 38 is opened automatically. One convenient way of doing this is to have the valves 28 and 38 connected to a common piston 60 arranged within a cylinder 61, the piston being normally biased by appropriate means, for example, a spring 62, so as to close the valve 38 and open the valve 28.
- 40 The valves 43, 47, and 51 are connected by any suitable means with secondary valves

63 in the by-pass, motive-fluid conduits 64 communicating with the cylinder 61 at the end opposite to the spring 62. It is obvious that, when any one of the valves 43, 47, and 51 is opened, a by-pass valve 63 is also opened and motive fluid passes through a conduit 64 to the cylinder 61, forcing the piston over and compressing the spring 62, thereby closing the valve 28 and opening the valve 38. The cylinder 61 preferably has a sufficiently loose fit with respect to the rod connecting the valves 28 and 38 that steam may escape therefrom, in order that the spring 62 may function to close the valve 38 and to open the valve 28.

45 The operation of apparatus embodying my invention is as follows: For high speed, motive fluid is expanded in one or more of the nozzles 23 and the velocity energy thereof is fractionally abstracted in the impulse section 13. Thereafter, the motive fluid is fractionally expanded by the reaction blading in the sections 14 and 15 of the high-pressure turbine unit 9, and is discharged into the exhaust chamber 26 from which it passes through the conduit 27 and the branch 31 to the turbine unit 11 and is then further fractionally expanded by the included portion of the reaction blading of the turbine unit 11. For low speed, motive fluid from the exhaust casing passes through the branch 29 to the low-pressure turbine unit 11. For intermediate speeds, any of the pairs of valves 33 and 34, 32 and 34, and 32 and 33 may be relatively so opened as to secure an equal division of power between the two turbine units.

50 For maneuvering, or in case of emergency, the valve 51 is opened to supply motive fluid directly to the low pressure turbine unit 11.

55 In order to operate astern, valves 43 and 47 are opened to supply motive fluid to the astern wheels 40 and 44.

60 The valves 28 and 38 are so inter-connected with the valves 43, 47 and 51 that if any of the latter is opened motive fluid is caused to flow to the cylinder 61 and moves the piston 60 over so as to close valve 28 and open the valve 38. As soon as the valve which has been open is closed, the supply of motive fluid to the cylinder 61 is cut off and the spring 62 automatically functions to move the piston over to close the valve 38 and open the valve 28.

65 From the foregoing, it will be seen that I have devised a compound turbine which is capable of operating at different speeds, thereby avoiding the necessity of using a special cruising turbine, and in which there is an equal division of power at different speeds.

70 While I have shown my invention in but one form, it will be obvious to those skilled in the art that it is not so limited, but is susceptible of various other changes and modifi-

cations, without departing from the spirit thereof, and I desire, therefore, that only such limitations shall be placed thereupon as are imposed by the prior art or as are specifically set forth in the appended claims.

What I claim is:

1. A turbine installation comprising a high-pressure turbine unit, a low-pressure turbine unit having blading at its high-pressure end progressively increasing in length and shorter than the low-pressure blading of the high-pressure unit, means for discharging motive fluid from the high-pressure unit to blading of the low-pressure unit of different lengths whereby operation at different speeds with equal division of power is secured. 70
2. A turbine installation comprising a high-pressure turbine unit, a low-pressure turbine unit having blading at its high-pressure end progressively increasing in length and shorter than low-pressure blading of the high-pressure unit, a conduit connected with the high-pressure unit, motive fluid inlets communicating with the conduit and adapted to discharge to low-pressure blading of different lengths whereby different back pressures at the low-pressure end of the high-pressure unit may be had, and means for controlling the inlets whereby the back pressure is so adjusted as to secure equal division of power between the two turbine units. 80
3. A turbine installation comprising a high-pressure turbine unit, a low-pressure turbine unit, means for conveying motive fluid discharged from the high pressure unit to the low pressure unit, said low pressure unit including a section having blading shorter than low-pressure blading of the high-pressure unit, a plurality of motive fluid inlets arranged along said section at such points as to develop such back pressures at the exhaust end of the high-pressure unit that equal divisions of power may be had between the units for operation at different speeds. 90
4. A turbine installation comprising a high-pressure turbine unit, a low-pressure turbine unit including a section having blading progressively increasing in length but shorter than low-pressure blading of the high-pressure unit, means for conducting motive fluid discharged from the high-pressure unit to said section so as to include varying numbers of rows of blading and develop varying back pressures whereby operation at different speeds with equal divisions of power may be secured. 100
5. A turbine installation comprising a high-pressure turbine unit, a low-pressure turbine unit including a series of stages having blading progressively increasing in length but relatively shorter than low-pressure blading of the high-pressure unit, a conduit connected with the high-pressure unit, a plurality of motive fluid inlets communicating with the conduit and arranged along said series of stages whereby different back pressures may be built up, and valves for controlling the inlets whereby different back pressures may be established and equal divisions of power secured for operation at different speeds. 110
6. In a turbine installation, a high-pressure unit, a low-pressure unit including a section having blading relatively shorter than low-pressure blading of the high-pressure unit, a conduit connected to the high-pressure unit for conducting motive fluid discharged therefrom to said section and including a plurality of branches communicating with the section at different points therealong, and valves in the branches, the branch nearest the low-pressure end of the section operating to so connect the turbine units as to develop full speed with equal power, the branch near the high-pressure end of the section being so located as to cause the turbine units to develop substantially low speeds and powers and the intermediate branch capable of operating in conjunction with the other branches in order that the turbine sections may develop substantially equal intermediate speeds with equal divisions of power. 120
7. In a turbine installation, a high-pressure turbine unit including ahead and reversing sections, a low-pressure turbine unit including ahead and reversing sections, connections for supplying motive fluid to the ahead section of the high-pressure unit, a connection for receiving motive fluid discharged from the high-pressure unit and conducting it to the high-pressure end of the ahead section of the low-pressure turbine unit, a valve in the last named connection, an independent connection for supplying motive fluid to the ahead section of the low-pressure turbine unit, connections for supplying motive fluid to the reversing sections, valves in the independent connections and the last named connections, and means associated with the independent connection and reversing inlet valves whereby when any of the latter are opened the valve in the connection between the turbine units is closed. 130
8. In a turbine installation, a high-pressure turbine unit including ahead and reversing sections and an exhaust casing, a low-pressure turbine unit including ahead and reversing sections and an exhaust casing, conduits for connecting the exhaust casing of the high-pressure unit with the ahead section of the low-pressure turbine unit and with the exhaust casing thereof, reciprocally operating valves in the conduits so that when one valve is opened the other is closed, an independent motive fluid connection for supplying motive fluid to the 125

low-pressure turbine unit, connections for supplying motive fluid to the reversing sections, valves in said connections, and means for operating the conduit valves so as to close the conduit between the exhaust cas-

ings of the high pressure unit and the ahead section of the low-pressure unit and open

the valve of the conduit between the exhaust casings when any of the valves of said connections are opened.

In testimony whereof, I have hereunto subscribed my name this first day of March, 1921.

HENRY F. SCHMIDT.
